WILLIAM C. BAXTER, OF BEVERLY, MASSACHUSETTS, ASSIGNOR TO UNITED SHOE MACHINERY COMPANY, OF PATERSON, NEW JERSEY, A CORPORATION OF NEW JERSEY.

SKIVING-MACHINE.

1,187,028.

Specification of Letters Patent. Patented June 13, 1916.

Application filed September 6, 1913. Serial No. 788,409.

To all whom it may concern:

Be it known that I, WILLIAM C. BAXTER, a citizen of the United States, residing at Beverly, in the county of Essex and State 5 of Massachusetts, have invented certain new and useful Improvements in Skiving-Machines; and I do hereby declare the following to be a full, clear, and exact description of the invention, such as will enable others 10 skilled in the art to which it appertains to make and use the same.

The invention relates to skiving machines for skiving the marginal portion of the sole of a boot or shoe to give the sole a lighter 15 or thinner appearance.

The object of the invention is to improve and simplify the construction of this type of skiving machine and to this end the invention consists in the features of construction and combinations of parts herein- 20 after described and set forth in the claims.

The features of the invention will be readily understood from an inspection of the accompanying drawings and the following 25 detailed description of the machine illustrated therein.

In the drawings: Figure 1 is a left hand side elevation of the machine embodying the various features of the invention in their 30 preferred form; Fig. 2 is a front elevation of the machine; Fig. 3 is a plan view of the forward part of the machine; Fig. 4 is a right hand side elevation of the parts shown in Fig. 3; Fig. 5 is a detail front elevation 35 with the channel flap guard removed; and Fig. 6 is a vertical sectional view on line 6—6, Fig. 5.

In the machine shown in the drawings the projecting edge of the sole is supported 40 upon a frusto-conical work supporting roll 1, the edge of which is shaped to enter the crease between the upper and sole and act as a guide for the shoe. A feed wheel 2 and presser foot 3 are arranged above the work 45 support and coöperate with the work support in feeding the marginal portion of the sole against the edge of a skiving knife 4. The skiving knife is secured in fixed relation to the feed wheel and presser foot so 50 that it acts to remove a skiving of substantially uniform thickness from the marginal surface of the sole.

In order that the work engaging devices may accommodate themselves to variations

in the thickness of the sole edge, provision 55 is made for a relative yielding movement between the knife and work support, and in accordance with the present invention this movement is such that it does not affect the angular relation between the knife and work support and does not, therefore, vary the angle of the skiving. The relative yielding movement is preferably secured by mounting the work support in a yielding carrier. As shown, the work support is secured upon 60 the lower end of an inclined shaft 5 mounted in a bearing block 6 which is secured to a vertically movable carrier block 7. The carrier block 7 is fitted to slide vertically between vertical guides 8 formed on the 65 frame of the machine and is provided with a depending cylindrical portion 9 fitting within a bore 10 in the frame. The carrier block is also provided with a depending rod 11 of smaller diameter than the cylindrical 70 portion 9 which extends down through a sleeve 12 which is screwed into the lower end of the bore 10. A spring 13 is interposed between the end of the sleeve 12 and the end of the cylindrical portion 9 and 75 serves to force the carrier block 7 and work supporting roll 1 upward into position to hold the work against the presser foot and the feed wheel. The upward movement of the work support is limited by a nut 14 80 screwed on the lower end of the rod 11 and normally engaging the lower end of the sleeve 12. The rod 11 is connected by a rod 15 with a treadle (not shown) by which the work support may be drawn downward 85 in inserting the work.

The work supporting roll is driven during the operation of the machine through a horizontal shaft 16 mounted in the carrier block 7 and provided at its forward end 90 with a beveled gear 17 engaging a similar gear 18 secured to the upper end of the shaft 5. The shaft 16 is driven from a shaft 19 mounted in fixed bearings in the frame of the machine and connected with the shaft 100 16 by an Oldham coupling 20 which continuously connects the shafts while permitting the work supporting carrier and shaft 16 to move vertically in accordance with the thickness of the sole operated upon. The 105 shaft 19 is connected by gears 22 with a driving shaft 21 which carries a tight pulley 23 and a loose pulley 24. The driving

shaft may be shifted by the operator from one pulley to the other by a belt shipper 25. The feed wheel and presser foot are carried upon a head 26 mounted upon the frame 5 of the machine above the shaft 19 and secured in fixed position on the frame by clamping bolts 27 which pass through slots 28 in the flanges 29 of the head. By loosening the bolts the head may be adjusted longitudinally of the shaft 19 or in a direction transversely of the feed to vary the position of the knife and feed wheel with relation to the work supporting and guiding roll 1 in accordance with the projection of the sole 10 operated upon. The feed wheel is mounted upon a stud 30 projecting from a depending bracket 31 which is secured to the front end of the head 26 by the securing screws 32. A pinion 33 is secured to the feed wheel and is engaged by a gear 34 secured to the front end of an actuating shaft 35 which is mounted in the head 26 and is driven from the shaft 19 through gears 36. By this construction and arrangement of the actuating shaft 25 and feed wheel adequate space is provided for the shaft 5 of the work support and for a comparatively long bearing for the shaft between the roll and the beveled gear 18 through which the shaft is driven. This also 30 enables the feed wheel and work support to be driven in the proper direction from the shafts 19 and 35 which are directly geared together. The gears 33 and 34 are inclosed and protected by a plate 37 which is secured to the front of the bracket 31 and is recessed on its rear side to surround the gears. The front side of the plate 37 is also recessed to partially surround the feed wheel 2 and supports a stripper finger 38, the end of which 35 projects into the annular groove in the face of the wheel. The plate 37 also supports the presser foot 3 which is provided with a shank fitting within a bearing 39 in the plate. The presser foot may be adjusted by a nut 40 screwed on to the upper end of the presser foot shank and provided with a flange 41 fitting within a groove 42 in the plate 37. The shank of the presser foot is held from turning within the bearing and is clamped in 45 position by a set screw 43 which engages a flat portion of the shank. A channel flap guard 44 is adjustably secured to the plate 37 by a clamping bolt 45 and is arranged to overlie the front face of the feed wheel.

50 In order that the skiving knife may be adjusted to bring its cutting edge into proper position to remove the desired skiving from the lower edge of the sole the knife is so mounted upon the fixed frame of the machine that it may be given a horizontal adjustment transversely of the direction of feed, an adjustment in the direction of the feed, an angular adjustment, and a vertical adjustment. The horizontal adjustment 55 transversely of the direction of the feed is

provided for by clamping the shank of the knife between jaws 46 of the supporting arm 47, the knife being held in adjusted position by a clamping screw 48. The adjustment of the knife in the direction of the line of feed is provided for by mounting the arm 47 on a guideway formed on a support 49 and securing the arm in position upon the support by a clamping bolt 50 which passes through a slot in the arm. The angular adjustment 70 of the skiving knife is provided for by mounting the support 49 upon a segmental guideway formed upon a slide 51 and securing the support in position by clamping bolt 52. The segmental guideway is so formed that it is substantially concentric with the end of the skiving knife and by adjusting the support 49 upon the segmental guideway the angular adjustment of the knife may be varied to produce the desired bevel upon the 75 lower outer edge of the sole. In order that the knife may be adjusted vertically, the slide 51 is mounted upon a vertical guideway formed on the frame of the machine. An adjusting screw 54 is provided for adjusting the slide 51 and the slide is secured in adjusted position by the clamping bolts 55.

In doing certain classes of work it is desirable that the crease gage be oiled or lubricated, and the machine is accordingly provided with an oiling device adapted to apply oil to both faces of the crease engaging portion of the crease guide. As shown, this device comprises an oiling pad 56 grooved to receive the edge of the work supporting and guiding roll and mounted in the end of a plunger 57. The plunger 57 is forced forward by a spring 58 and is provided at its rear end with a pin 59 adapted to fit within grooves 60 formed in a boss 61 on the carrier block 7. In case it is desired to throw the oiling device out of action the operator may force the plunger 57 back and turn it so that the pin 59 rests against the end of the boss 61 and holds the oiling pad out of engagement with the work supporting roll.

In order that the skiving may be properly directed away from the cutting point a guard plate 62 is secured to the plate 37 and is arranged to extend along the upper side of the 115 knife in the direction of the feed.

While it is preferred to employ the construction and arrangement of devices shown and described, it is to be understood that this construction and arrangement is not material except so far as it may be specified in the claims and may be varied and modified without departing from the broader features of the invention.

Having explained the nature and object 125 of the invention and specifically described one form of machine in which it may be embodied, what I claim is:

1. A skiving machine, having in combination, a work support constructed to support 130

the marginal portion of an attached shoe sole, a skiving knife, said support and knife being relatively yielding toward and from one another in normally fixed angular relation, and means for adjusting the angular relation of knife and support to vary the angle of the skiving, substantially as described.

2. A skiving machine, having in combination, a combined crease guide and work support, a skiving knife, said support and knife being relatively yielding toward and from one another in normally fixed angular relation, and means for adjusting the relative angular relation of knife and support, substantially as described.

3. A skiving machine, having in combination, a frame, a feed wheel rotatively mounted therein, a skiving knife mounted on the frame and angularly adjustable thereon, a work support movable toward and from the skiving knife in normally fixed angular relation with respect thereto, and means for actuating the feed wheel, substantially as described.

4. A skiving machine, having in combination, a work support, means for rotating the same, a feed wheel and actuating means therefor, a skiving knife normally held in fixed angular relation to the feed wheel, and a yielding mounting for the work support for maintaining the latter in fixed angular relation to the feed wheel and skiving knife irrespective of the thickness of the work, substantially as described.

5. A skiving machine, having in combination, a feed wheel mounted to rotate about a fixed axis, actuating devices for said wheel, a skiving knife normally held in fixed position, a frusto-conical work support having its conical surface opposed to the feed wheel and skiving knife, a carrier in which said support is rotatably mounted, said carrier being movable in a right line toward and from the feed wheel and skiving knife to accommodate varying thicknesses of work, and driving mechanism including a coupling for actuating the work support, substantially as described.

6. A skiving machine, having in combination, a skiving knife, a pair of superposed actuating shafts, driving mechanism for one of said shafts, a pair of gears directly connecting said shafts, a gear secured to the front end of the upper of said shafts, a feed wheel, a gear secured thereto and located below and meshing with the gear on the upper shaft, a frusto-conical work support mounted to turn about an inclined axis, and connections including bevel gearing between the work support and the lower of said actuating shafts, substantially as described.

7. A skiving machine, having in combination, a skiving knife, a pair of actuating shafts mounted to turn about fixed axes,

driving mechanism for one of said shafts, a pair of gears directly connecting said shafts, a feed wheel, a gear connected therewith, a gear secured to the front end of one of said actuating shafts and meshing with the feed wheel gear, a frusto-conical work support mounted to turn about an inclined axis, bevel gearing for actuating said support, a movable carrier for said support and gearing, and a coupling between said gearing and the front end of the other of said actuating shafts, substantially as described.

8. A skiving machine, having in combination, a frame, a skiving knife, a pair of actuating shafts mounted to turn in fixed bearings in the frame, driving mechanism for said shafts, a depending bracket secured to the front of the frame, a bearing stud in said bracket located beneath the front end of one of said shafts, a feed wheel and gear secured thereto mounted on said stud, a gear on said shaft meshing with the feed wheel gear, a frusto-conical work support located beneath the feed wheel and mounted to turn about an inclined axis, a shaft for the work support, a bevel gear secured to said shaft, a bearing for said shaft intermediate the work support and the gear, a movable carrier for said bearing, a guideway for the carrier secured to the frame of the machine, and connections between the bevel gear and the other of said actuating shafts, substantially as described.

9. A skiving machine, having in combination, a frame, a shaft and gear mounted to turn about a fixed axis in said frame, a work support actuated by said shaft, a skiving knife, a head mounted upon the frame and adjustable in a direction parallel with the shaft, a second shaft carried by the head, a gear on said shaft meshing with said first mentioned gear, and a feed roll carried by the head and actuated by said second shaft, substantially as described.

10. A skiving machine, having in combination, a feed wheel, a skiving knife, a frusto-conical crease guide and work support, means for actuating said guide and support, and an oiling device having means for applying oil to both faces of the crease engaging portion of the crease guide, substantially as described.

11. A skiving machine, having in combination, a feed wheel, a skiving knife, a frusto-conical crease guide and work support mounted to turn about a rearwardly inclined axis, means for actuating the guide and support, and a spring-pressed oil-applying pad located in the rear of said guide and arranged to contact with the welt engaging face of said guide and support, and means under the control of the operator for holding the pad out of contact with the guide and support, substantially as described.

12. A skiving machine, having in combination, a frusto-conical crease guide and work support, a skiving knife, a head, a rotary feed wheel carried by the head, a 5 presser-foot and a channel guide, both carried by the head, and means for adjusting the head relatively to the crease guide and

work support in a direction parallel with the axis of the feed wheel, substantially as described.
